Primary Examiner — Paula Allen Greene*(74) Attorney, Agent, or Firm* — ScienBiziP, P.C.(57) **CLAIM**

The ornamental design for a headset, as shown and described.

DESCRIPTION

FIG. 1 is a front, right, and top perspective view of a headset, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a loudspeaker.

FIG. 10 is a partial enlarged view of an area labeled 10 in FIG. 1 comprising a regulator; and,

FIG. 11 is a partial enlarged view of an area labeled 11 in FIG. 2 comprising a microphone.

The broken lines shown in the drawings are included for the purpose of illustrating portions of the headset that form no part of the claimed design.

The dot-dash broken lines encircling portions of the headset in FIGS. 1 and 2 and illustrated in enlarged views in FIGS. 9, 10, and 11 form no part of the claimed design.

1 Claim, 11 Drawing Sheets(56)
